CLAIM

The ornamental design for a Christmas wreath figure, as shown and described.

DESCRIPTION

FIG. 1 is a front, elevational view of a Christmas wreath figure showing my new design therefore, the bows being shown as environment and forming no part of the design; FIG. 2 is a side elevational view thereof, the opposite side being an identical mirror image; FIG. 3 is a top plan view thereof; and, FIG. 4 is a bottom plan view thereof.
